UNITED STATES PATENT OFFICE.

GERALD W. HART, OF HARTFORD, CONNECTICUT, ASSIGNOR TO THE HART & HEGEMAN MANUFACTURING COMPANY, OF SAME PLACE.

ELECTRIC SWITCH.

SPECIFICATION forming part of Letters Patent No. 549,237, dated November 5, 1895.

Application filed March 19, 1895. Serial No. 542,383. (No model.)

To all whom it may concern:

Be it known that I, GERALD W. HART, a citizen of the United States, residing at Hartford, in the county of Hartford and State of Connecticut, has invented certain new and useful Improvements in Electrical Switches, of which the following is a specification.

The invention relates to the class of electrical switches that are more particularly adapted and intended for incandescent circuits and are known as "flush switches" or "cut-outs."

The object of the invention is to provide a simple, cheap, and efficient means for holding the cap, cover, or flush-plate tightly in place without screws over the wall or holding plate of a switch of this class; but of course the invention is equally applicable to switches of other classes.

To this end the invention resides in a switch or cut-out having a cap or flush-plate for covering and concealing the mechanism and a wall or holding plate, with a spring or other elastic part interposed between the cap or flush-plate and a shoulder on the operating key or handle spindle of the switch, as more particularly hereinafter described, and pointed out in the claims.

Referring to the accompanying drawings, Figure 1 is a plan of a flush-switch embodying the invention. Fig. 2 is an elevation with parts cut in section to show the interior of the same. Fig. 3 is a plan with the flush-plate and the handle or key removed. Fig. 4 is an enlarged detail section of the wall-plate, flush-plate, handle or key, and operating-spindle. Fig. 5 is a similar view of a modified arrangement of the invention; and Fig. 6 is a plan of the inside of a flush-plate, illustrating another arrangement of the invention.

In the views, 1 indicates a base, which is usually made circular in outline, of porcelain or other suitable insulating material. This base supports any desired number of binding-posts 2, of any common form, for the attachment of the circuit-wires, with conducting-pieces 3 for contact with the movable poles of the switch. The base also supports a rotary spindle 4, which bears the movable poles 5, that, either single or double, as the case may be, make and break contact with the contact-

pieces connected with the binding-posts as the spindle is rotated by turning the handle or key 6. In the form illustrated in the drawings a single-pole switch of common form is 55 shown; but the interior mechanism or operating parts of the switch for making and breaking the circuit have no immediate connection with and are not material to the invention.

Arranged around the base is a sheet-metal shell 7, that protects the interior mechanism from dust and dirt, and on the outer edge of this is the wall-plate 8, that is held to the base by screws 9. This wall-plate is usually cast 65 to shape of brass or other similar material and is provided with perforations for the passage of the screws that are employed to hold the switch in place in its socket in the wall of the room or apartment in which it is located, 70 this class of switch usually being set into a wall, so the holding or wall plate is smooth with the wall.

A highly-finished flush or surface plate 10 is provided to cover the mechanism and the 75 wall or holding plate. This flush-plate is usually stamped to shape from sheet metal a little larger than the wall-plate, with its edges turned back and its center depressed or recessed, so the handle or key will not have 80 to project out but slightly beyond the surface of the flush-plate. After the wall-plate has been secured in place by screws or other means this flush or surface plate of finished sheet metal, without openings except for the 85 passage of the spindle, is placed over the whole and the handle or key then attached to the spindle by any common means.

In the form of switch illustrated the handle or key for rotating the spindle and making tense the pole-throwing spring is provided with a shank 11, with a threaded socket that is screwed on the threaded end of the spindle. On the shank of the handle is a loose collar 12, and thrusting against this collar and the inner edge of the handle is a spring or elastic washer 13. This spring or elastic washer thrusts the collar inward, so that when the handle is secured upon the spindle of the switch the collar is forced 95 against the face of the flush-plate with a yielding pressure in such manner as to hold the

flush-plate in position tightly against the wall or holding plate and yet without interfering with the free rotation of the handle and spindle for operating the switch.

- 5 In the form shown in Fig. 5 the loose collar and the spring or elastic washer are held in a chamber 14, formed around the spindle-perforation through the flush-plate, and this elastically-held collar presses against a shoulder 15 on the shank of the handle when the latter is attached to the spindle, so that the flush-plate is held in place close against the wall or holding plate with a similar yielding pressure.
- 15 In the form shown in Fig. 6 the collar 16 is held by spring-arms 17, that are formed integral with the collar and are secured to the inside of the flush-plate.
- By means of this construction a thin, cheap, 25 and highly-finished sheet-metal flush-plate can be tightly held in place without screws or other visible means of attachment, so as to cover a rough wall-plate and protect the interior from the entrance of dust and dirt.
- 25 There will be no rattle to the flush-plate and the handle can be turned without restriction. This arrangement does not require any special fitting of the parts and the plate is held tightly in position without necessitating that 30 the handle shall be screwed upon the spindle to just such a predetermined location as would be necessary to hold the plate without this elastic arrangement. The handle, when provided with this arrangement for holding 35 the flush-plate, does not bind if it tends to screw inward farther than usual, and the plate will not be loose and shake and rattle if the handle does not screw in as far as usual. This invention is particularly advantageous 40 in the construction of gang flush-switches, for in those cases it is almost impossible to so make the parts that the handles shall all

screw on the spindles just the same; but with the present invention a large plate having a number of handles or keys can be securely held, with each handle doing its part in retaining the plate in position.

I claim as my invention—

1. An electric switch having an operating handle spindle supported by the base, with 50 a cover loosely placed over the face of the switch, and an elastic connection between the operating handle spindle and the cover, said elastic connection thrusting the cover with a yielding pressure toward the base and 55 away from the handle, substantially as specified.

2. An electric switch having an operating handle spindle supported by the base, with 60 a cover loosely placed over the face of the switch, and a spring depressed collar between the handle and the cover, said collar thrusting the cover toward the base with a yielding pressure, substantially as specified.

3. An electric switch having a holding plate 65 provided with means for securing the switch in position, a handle for operating the switch, a flush plate for covering the holding plate, and an elastic connection between the handle and the flush plate for holding the latter in 70 position against the holding plate, substantially as specified.

4. An electric switch having a base bearing a holding plate, a rotary spindle for moving the poles of the switch, a handle for rotating 75 the spindle, and a flush plate for covering the mechanism and the holding plate, a movable collar bearing against a portion of the operating spindle, and a spring for thrusting the movable collar, substantially as specified.

GERALD W. HART.
